UNITED STATES PATENT OFFICE

HARRY JOHAN HJALMAR NATHORST, OF STOCKHOLM, SWEDEN, ASSIGNOR TO AKTIE-BOLAGET NORDISKA ARMATURFABRIKERN, OF STOCKHOLM, SWEDEN, A COMPANY REGISTERED IN SWEDEN

PRESSURE CAN

Application filed February 27, 1929, Serial No. 343,001, and in Sweden February 28, 1928.

Of late it has become increasingly usual to lubricate pneumatic tools, rock drills, coal pick hammers, and so forth, by introducing into their cylinders or into passageways bordering the same, certain kinds of so-called thick or consistent grease, that is to say, more or less viscous lubricants. Hitherto there has been a want, however, of a handy and easily transportable grease can or lubricator for this purpose. In order that such a grease can shall be fully suited to its purpose, it should be such, at least when made in small sizes, that it can be carried in the pocket, and for this reason, inter alia, it should be so constructed that no grease will be pressed out of the can when it is not used, even if the can is inadvertently subjected to pressure. Furthermore, the spout of the can should be arranged in such manner that it is protected against damage as far as possible, when the can is not used.

Now, the present invention relates to a pressure can which fully answers these requirements, and which is capable of being used not only for lubricating the above mentioned and other machines with lubricating grease, but which may also be used with advantage for portioning out other plastic pastes or bodies. The improved pressure can or grease gun comprises a can for receiving lubricant or paste, and a slidable bottom in said can, and is principally characterized by that the spout is slidably mounted in said can as well as in said bottom in such manner that the spout may be pulled out to project beyond the can and may be pushed into the can, said spout being provided with at least one opening within said can located in such manner that in the pulled-out position of the spout said opening affords communication between the interior of the can and the spout, while in the pushed-in position of the spout said opening is covered by the bottom so that the interior of the can is shut off from communication with the spout.

This arrangement is suitably carried out in such manner that the spout is slidably mounted in the cap of the can, and is pro-

vided within the can with one or more side openings, while the slidable bottom is provided with an opening in which the spout fits tightly, so that the bottom may be pushed in over the spout for the purpose of pressing out the grease or paste. 55

An embodiment of the invention is illustrated in the accompanying drawings by way of example. Fig. 1 is a longitudinal section through a pressure can or grease gun according to the invention, and Fig. 2 is a side view of the same. 60

The grease or paste to be portioned out is kept in the space 1 which is enclosed by the cylindrical can shell 2, bottom 3, cap 4, and spout 5. The latter is provided with a number of side openings 6 through which the grease in the space 1 may enter the spout 5. The bottom 3 is secured to, or made in one piece with, a sleeve 7 which also has an outer bottom 8. Inserted between the bottoms 3 and 8 is a central tube 9 which is open at its upper end which is secured to the bottom 3. The sleeve 7 is provided with one or more longitudinal slots 10 which are engaged by screws 11 screw-threaded through the can shell 2, so that said screws and slots limit the sliding motion of the bottom 3 in the can. Secured to the spout 5, which is provided with a bottom 12, are a guide ring 13 and a stop ring 14 of equal diameters, the former of which serves to guide the spout in the tube 9, while the ring 14 serves as a stop for the spout when pulled out through the cap 4. 70 75 80

The cap 4, which may suitably be provided with a nubbed edge, is shown as adapted to be attached to the can 2 by means of a bayonet lock, consisting of pins 15 secured to the can wall and which engage angular slots 16 in the can. The cap can thus easily be taken off and put on. The spout 5 is slidable in a central opening in the cap 4, so that it may be pulled out and pushed in, its outward movement being limited by the stop ring 14, as above explained, and its inward movement being limited by its nozzle 17. A packing ring 18 of felt is provided in the cap and serves to prevent the grease from passing out. 85 90 95 100

around the spout. The bottom 8 is provided with an air vent 19 in order to avoid pressure or vacuum arising in the tube 9 when the spout is displaced.

- 5 The grease can is made ready for use by taking off the cap 4 with the spout 5, and by pushing the bottom 3 so far down as the slots 10 and screws 11 will admit. The sleeve 7 is now turned relatively to the can 2, so that the screws 11 engage the upper lateral portions of the slots 10, and thus prevent the can 2 from moving downwards by its own weight, when the can is placed on the bottom 8. A wooden pin, iron rod, or 15 the like, is now inserted in the tube 9 in order to prevent a lubricant from passing down into said tube. The space 1 is now filled with grease which is quite easily done, since said space has a comparatively small 20 depth in proportion to its width.

When the space 1 has been filled, the above mentioned pin or the like is removed, the spout 5 is carefully pushed into the tube 9, and the cap 4 is put on and secured by the 25 aid of the above mentioned bayonet lock. Finally, the sleeve 7 is turned back so far that it can freely be moved in the axial direction in the can 2.

When the grease can is afterwards to be 30 used the spout 5 is pulled out so far that the stop ring 14 comes to bear against the inside of the cap 4, after which pressure is applied to the bottom 8. The grease is thereby pressed from the space 1 through 35 the opening 6 into the spout 5 and out through said spout and the nozzle 17 to the grease hole of the machine or apparatus in question. When the can is no more to be used, the spout 5 is again pushed in as far 40 as the nozzle 17 will admit. The spout now projects so little outside the cap that it is protected against damage as far as possible, and the openings 6 are closed by the wall of the tube 9, so that no grease can be pressed 45 out of the can when the spout is pushed into the same.

It will thus be evident that the can is very easily filled as well as convenient to handle, owing to the spout being adapted to be 50 pushed in, and when pushed in, also closing the can. The can may thus easily be transported without risk of any portion of its contents flowing out if the can is inadvertently upset, or if the bottom 8 is inadvertently subjected to pressure. When made in a suitable size the can can thus be carried in a pocket without risk.

In certain cases, when lubricating grease or other pastes are concerned, the same may 60 be so viscous that more force is required in order to press out the same than what can conveniently be produced by pressure applied directly to the bottom 8. In such cases, the can wall 2 may be provided, for instance, 65 with interior threads, and the sleeve 7 with

exterior threads, and the bottom 3 may be forced inwards as required simply by turning the sleeve 7 relatively to the can 2. In this case the slots 10 and screws 11 are of course omitted, the function of the can otherwise remaining the same. Instead of providing the can 2 and sleeve 7 with screw-threads, a strap may be rigidly or pivotally attached to the can 2, such strap extending outside the bottom 8, and a screw or rotatable eccentric disk may be provided in the same by means of which the sleeve 7 and bottom 3 may be forced inwards into the can.

In the embodiment illustrated the can is 80 supposed to have a circular cross section, but it will be understood that it may also be made an oval or edged cross section.

I claim:

1. In a pressure can, the combination of 85 a can for receiving lubricant or other paste, a bottom slidable in said can, and a substantially tubular spout slidably mounted in said can as well as in said bottom in such manner that said spout may be pulled out 90 to project beyond said can and may be pushed into the can, said spout being provided with at least one opening within said can located in such manner that in the pulled-out position of said spout said opening affords communication between the interior of said can and said spout while in the pushed-in position of said spout said opening is covered by said bottom so that the interior of said can is shut off from communication with said spout.

2. In a pressure can, the combination of 95 a can for receiving lubricant or other paste, a bottom slidable in said can, a substantially tubular spout slidably mounted in said can 100 as well as in said bottom in such manner that said spout may be pulled out to project beyond said can and may be pushed into the can, said spout being provided with at least one opening within said can located in such manner that in the pulled-out position of said spout said opening affords communication between the interior of said can and said spout while in the pushed-in position of said spout said opening is 115 covered by said bottom so that the interior of said can is shut off from communication with said spout, and a stop ring attached to said spout and adapted to limit the outward displacement of said spout relatively to said can, said spout having such length that in such position it still retains engagement with said bottom.

3. In a pressure can, the combination of 120 a can for receiving lubricant or other paste, a bottom slidable in said can, a substantially tubular spout slidably mounted in said can 125 as well as in said bottom in such manner that said spout may be pulled out to project beyond said can and may be pushed into the 130

can, said spout being provided with at least one opening within said can located in such manner that in the pulled-out position of said spout said opening affords communication between the interior of said can and said spout while in the pushed-in position of said spout said opening is covered by said bottom so that the interior of said can is shut off from communication with said spout, a tube tightly fitting said spout and attached to said slidible bottom, and said spout having a bottom closing the inner end of the same.

4. In a pressure can, the combination of
15 a can for receiving lubricant or other paste,
a bottom slidable in said can, a substantially tubular spout slidably mounted in
said can as well as in said bottom in such
manner that said spout may be pulled out
20 to project beyond said can and may be
pushed into the can, said spout being provided
with a least one opening within said
can located in such manner that in the
pulled-out position of said spout said open-
25 ing affords communication between the in-
terior of said can and said spout while in
the pushed-in position of said spout said
opening is covered by said bottom so that
the interior of said can is shut off from
30 communication with said spout, a sleeve at-
tached to said slidible bottom, said sleeve
having at least one longitudinal slot, and
at least one screw screw-threaded through
said can and engaging such slot.
